UNITED STATES PATENT OFFICE.

ERASmus O. PEOPLES, OF NEW YORK, N. Y., ASSIGNOR TO NEW YORK AND BROOKLYN
CASKET CO., OF BROOKLYN, NEW YORK, A CORPORATION OF NEW YORK.

DESIGN FOR A PANEL FOR CASKET-COVERS.

40,287.

Specification for Design.

Patented Oct. 5, 1909.

Application filed August 6, 1909. Serial No. 511,656. Term of patent 7 years.

To all whom it may concern:

Be it known that I, ERASmus O. PEOPLES, a citizen of the United States, and resident of the borough of Brooklyn, county of Kings, city and State of New York, have invented a new, original, and ornamental Design for a Panel for Casket-Covers, of which the following is a specification.

Reference is to be had to the accompanying drawing which shows in Figure 1 a perspective top view and in Fig. 2 a perspective end view of a panel showing my new design.

The central portion is open, as shown, in order that the coffin top may be visible through the panel when the panel is in place.

I claim:

The ornamental design for a panel for casket cover as shown.

ERASmus O. PEOPLES.
